UNITED STATES PATENT OFFICE.

SHERMAN S. JEWETT, OF BUFFALO, NEW YORK, ASSIGNOR TO JEWETT & COMPANY, OF BUFFALO, NEW YORK.

STOVE BASE.

Application filed March 25, 1925. Serial No. 18,288.

To all whom it may concern:

Be it known that I, SHERMAN S. JEWETT, a citizen of the United States, residing at Buffalo, in the county of Erie and State of New York, have invented a new and useful Improvement in Stove Bases, of which the following is a specification.

This invention relates to improvements in stove bases or supports, and particularly 10 to that class of stove bases which are formed of a plurality of separate cast side sections or spreaders detachably connected to and alternating with a plurality of cast leg sections or standards. Stove bases of this 15 character have heretofore been provided in which the alternating sections and legs were formed with interfitting or interlocking parts, adapted to be assembled and then held together by means of a single bolt or 20 other securing device passing through two adjacent overlying parts. In these previous constructions, however, the parts have been relatively complicated, and necessitated the use of heavy castings, difficult and expensive to produce, and requiring much finishing or grinding to obtain accurate fitting.

Some objects of the present invention are to construct an improved stove base of the character described, having side and end 30 members or spreaders and leg or supporting members of relatively light weight and simple construction, and to provide these members with interfitting parts adapted to connect the sections together to form a rigid base and to form these interfitting parts so 35 that both lateral and endwise relative movements between the parts are prevented.

It is often the practice, at the present time, to provide the stoves or stove bases 40 with an enamel, porcelain or other smooth, sanitary finish, and a further object of the invention is to construct the interfitting or interengaging sections so that, when assembled, the joints between the parts will 45 be substantially straight and vertical and as inconspicuous as possible, thus avoiding angular joints which would be difficult to fit closely and which would be unsightly, and to further this end, the interfitting parts of 50 the sections are so formed that the outer faces of the sections will be flush and form a substantially continuous surface.

Other objects of the invention are to improve stove bases and simplify their con-

struction in the other respects hereinafter 55 specified and claimed.

In the drawings:

Fig. 1 is a top plan view of a stove base embodying the invention.

Fig. 2 is a side elevation thereof.

Fig. 3 is a perspective view of one of the leg sections and portions of the adjacent side or spreader sections.

Fig. 4 is a fragmentary horizontal section of portions of two interengaging sections of 65 the stove base on line 4-4 Fig. 5.

Fig. 5 is a horizontal section, on an enlarged scale, of the base, viewed upwardly on the line 5-5 Fig. 6.

Fig. 6 is a vertical, sectional elevation of 70 one of the legs and the adjacent parts of the base on line 6-6 Fig. 5.

Fig. 7 is a fragmentary face view of two adjoining sections showing the securing means for holding the interlocked sections 75 in operative relation.

Fig. 8 is a view similar to Fig. 6 of a slightly modified construction.

Fig. 9 is a horizontal section on line 9-9 80 Fig. 8.

In the embodiment of the invention illustrated, a stove base of rectangular form is shown, having opposite horizontal end sections 10 and 12 and opposite horizontal side sections 11 and 13 alternately arranged 85 to interlock with three leg sections or supports 14 and a fourth leg section 14^a. While the invention is shown in connection with a rectangular base, it may be used in connection with round, elliptical or other shapes 90 of sectional stove bases.

The side and end sections 10-13 are provided with abrupt and straight, vertical edges 16 and the legs 14, 14^a are formed with similar side edges 17 adapted to abut 95 against the edges 16 and to be held in this position by interfitting means on the members, so as to form a rigid base with the outer faces and top and bottom edges of the interengaging sections flush and in alignment. For this purpose, in the construction shown, each of the sections 10, 11 and 12 is provided at each end, near the edge 16, with a lug 20 extending from the inner face and having a side face 21, while the section 13 is provided with a lug 20 at one 100 end only. The legs 14 are each provided with a pair of oppositely directed parts one 105

of which extends laterally beyond each edge 17, and is adapted to overhang and engage the face 21 of the adjacent lug 20 of the cooperating side or end section so as to prevent relative lateral movements between the legs and side or end sections. In Figs. 1-7 these lateral extensions on the legs are in the form of apertured lugs or loops 22 which are so proportioned that they will fit snugly over the lugs 20 with the end bar 23 of the loop engaging the face 21 of said lug, thus preventing lateral spreading or separation of the parts when the base is assembled. The member 13 is provided with only one of the lugs 20 adjacent one of its edges 16, the other edge having a part constituting a portion of the securing means employed for holding the assembled base together, as will be later described.

20 The means shown for preventing relative vertical displacement of the legs and the adjacent side members comprises a pair of spaced, vertically aligned lugs 25 projecting from the inner faces of the sections 10-13 adjacent the ends thereof so as to engage the opposite outer or top and bottom edges of the apertured lugs 22, so that when the parts are assembled, these interengaging parts 22 and 25 will effectually prevent relative vertical movements of adjacent members.

In the modified construction shown in Figs. 8-9, the loops 22 are replaced by lugs 28 having hooked or bent over ends 29 adapted to hook over the lugs 20 to prevent lateral displacement of parts, while the lugs 25 on the side sections engage the side edges of the lugs 28 as in the previous construction, for preventing relative vertical movements between adjacent members.

It is obvious that the lugs 20 and 25 could be formed on the leg sections 14, 14^a and the cooperating lugs or loops 22, or hooked lugs 28 could be arranged on the side and end sections if desired.

As before stated, it is desirable that the outer faces of the adjoining sections of the base should be flush and substantially continuous and that the joints between the edges 16 and 17 are as inconspicuous as possible. To insure this condition, alternate members of the base, such, for example, as the side sections 10-13, are provided with offset, laterally extending lugs 32 each having an outer flat face 33 adapted to be engaged flatwise upon the inner face of the adjoining leg section, see Fig. 4. Any number of these lugs may be provided, but preferably the sections have an upper and a lower lug at each end as shown, this arrangement being adapted to securely maintain the outer faces flush and aligned.

Means of simple construction and of easy operation are provided for securely holding the base in its assembled form, the

means shown comprising a lug 35 similar in form to the lugs 32, which is formed or secured on one end of the section 13 so as to lap over the edge portion of the adjacent leg 14^a in engagement with its inner face. The lug 35 and the leg 14^a are provided with registering holes for the reception of a stove bolt or nut 37, see Figs. 5 and 7.

When the stove base is to be assembled, the sections are successively connected; for instance, starting with the leg 14^a, the end section 10 is engaged therewith by presenting the end section angularly to the leg section from the outer side with their top and bottom edges in alignment and the lugs 32 extending inwardly over the adjacent edge of the leg. Then by swinging the section 10 to its operative, right angle position relatively to the leg, the lug 20 will enter the overhanging apertured lug 22 and the lugs 25 will engage the sides of said lug. Thus these two sections will be interlocked in such a way that no relative lateral, vertical, or in and out movements can occur between the sections. The remaining sections and legs are connected in a similar manner until only that end of the section 13 having the lug 35 thereon remains to be engaged with the leg 14^a. This is done by directing the lug 35 into position against the inner face of said leg, and then by inserting the bolt 37 and securing the nut thereon, all of the sections and legs will be rigidly connected together.

A stove base having leg sections provided with the modified lugs 28 is assembled in a similar manner.

I claim as my invention:

1. An interlocking connection between the leg member and the side member of a stove base, one of said members having a part adapted to interlock with a projection on the other member to hold said members against lateral separation, lugs on said other member engaging the upper and lower edges of said interlocking part to hold said members against relative vertical displacement, and means on one of said members adapted to engage the other member to hold the faces of said members in alignment.

2. An interlocking connection between the leg member and the side member of a stove base, one of said members having a part adapted to interlock with a projection on the other member to hold said members against lateral separation, lugs on said other member engaging the upper and lower edges of said interlocking part to hold said members against relative vertical displacement, and lugs on one of said members adapted to engage a face of the other member to hold the faces of said members in alignment.

3. An interlocking connection between the leg member and the side member of a stove

base, one of said members having a part on the inner face of one of said members adapted to extend upon the inner face of said other member and which holds said members against relative lateral and vertical displacement, said part overlapping a projection on the inner face of said other member, and means on one of said members adapted to engage the other member to hold 10 the outer faces of said members in alinement.

4. An interlocking connection between the leg member and the side member of a stove base, one of said members having a part 15 adapted to interlock with a projection on the other member to hold said members against lateral separation, lugs on said other member engaging the upper and lower edges of said interlocking part to hold said members 20 against relative vertical displacement, means on one of said members adapted to engage the other member to hold the faces of said members in alinement, the adjacent, contacting edges of said members being 25 straight and disposed in a substantially vertical plane so as to form an inconspicuous joint.

5. An interlocking connection between the leg member and the side member of a stove 30 base, one of said members having a part adapted to interlock with a projection on the other member to hold said members

against lateral separation, lugs on said other member engaging the upper and lower edges of said interlocking part to hold said members 35 against relative vertical displacement, lugs on one of said members adapted to engage a face of the other member to hold the faces of said members in alinement, the adjacent contacting edges of 40 said members being substantially straight and disposed in a vertical plane, and said interlocking and interengaging parts on said members being disposed on the rear faces of said members whereby an inconspicuous joint is formed and whereby the outer faces of said members present a substantially continuous and unbroken surface. 45

6. An interlocking connection between the leg member and the side member of a stove 50 base, one of said members having a part on its inner face adapted to interlock with a projection on the inner face of the other member to hold said members against lateral separation, lugs on the inner face of 55 said other member engaging opposite edges of said interlocking part to hold said members against relative vertical displacement, and lugs on the inner face of one of said members adapted to extend upon the inner 60 face of the other member to hold the outer faces of said members in alinement.

SHERMAN S. JEWETT.
